[57] **CLAIM**

The ornamental design for a calorie and fat gram counting dial for a wristwatch, as shown and described.

DESCRIPTION

FIG. 1 is a top view of the calorie and fat gram counting dial for a wristwatch embodying the present design. The watch, bezel, surface indicia on the bezel and strap are shown in broken lines as an environment structure and form no part of the claimed design; and,

FIG. 2 is an enlarged top plan view of the dial shown in FIG. 1. The dial has numeric increments of hundreds displayed and representing caloric increment counting. The dial has a window formed therein for a numerical count of fat grams to be displayed.
